PORTRABLE SPREADER FOR SEEDS, FERTILIZER PELLETS AND THE LIKE

William D. Love, Jr., Orinda, Calif.
(2002 Davis St., San Leandro, Calif.)

Filed Nov. 4, 1960, Ser. No. 62,737

Term of patent 14 years

(Cl. D31—3)

Fig. 1

Fig. 2

Fig. 3

Fig. 5

Fig. 4

FIGURE 1 is a front perspective view taken from the top and one side of a portable spreader for seeds, fertilizer pellets and the like, embodying my new design.

FIGURE 2 is a side elevational view thereof;

FIGURE 3 is a front elevational view thereof;

FIGURE 4 is an elevational view thereof showing the side opposite that shown in FIGURE 2; and

FIGURE 5 is a rear elevational view thereof.

I claim:

The ornamental design for a portable spreader for seeds, fertilizer pellets and the like, as shown.
